1911 INVENTOR

A. J. Morlock
BY *Frank McGrath*
ATTORNEY

UNITED STATES PATENT OFFICE.

ALBERT J. MORLOCK, OF BROOKLYN, NEW YORK.

SEPARATOR-PRESS.

1,231,929.

Specification of Letters Patent.

Patented July 3, 1917.

Application filed February 6, 1915. Serial No. 6,406.

To all whom it may concern:

Be it known that I, ALBERT J. MORLOCK, a citizen of the United States, residing at Brooklyn, county of Kings, State of New York, have invented certain new and useful Improvements in Separator-Presses; and I do hereby declare the following to be a true, clear, and exact description thereof.

My invention relates to an apparatus for separating liquid from solid matter in treating garbage, packing house refuse and the like, the liquid being pressed out of the solid matter and the solid material subsequently removed from the press in an expeditious manner.

My invention consists in the construction and combination of parts more particularly described and claimed.

Referring to the drawings forming a part of this specification;

Figure 1., is a longitudinal section through the apparatus.

Fig. 2., is a sectional view on an enlarged scale, of that portion of the pressing cylinder showing the means for draining the liquid during the pressing operation.

Fig. 3., is a section of the pressing mechanism similar to that shown in Fig. 1 with the pressing ram or plunger in the position prior to the pressing operation.

Fig. 4., is a section on line 4—4 of Fig. 1.

Fig. 5., is a section on line 5—5 of Fig. 1.

Fig. 6., is a detail of the end of the pressing cylinder, with the cylinder head in its detached position.

In the drawings like reference characters indicate like parts in the several views.

A is the pressing mechanism, B the base consisting as shown of a channel bar, although any other suitable construction may be used and C is the feed tank in which the material to be operated on is collected and from which it is fed to the pressing mechanism. D is a cylinder supported by brackets 11 and 12 which are secured by bolts 13 to the base B and provided with a feed opening 14. Surrounding the cylinder 10 is a sleeve 15 similar in shape to a T coupling, the flange 16 of which is provided with screw threads 17. The opening 18 of the sleeve is concentric of the opening 16 in the cylinder 10. The sleeve is held in place between the two supporting brackets 11 and 12. In the wall at one end of the cylinder 10 are perforations 19 and the inner surface of this part of the cylinder is reamed out at 20 to

form a seat in which fits a cylindrical perforated screen 21, the ends of which may be provided with outturned flange 22 which fits closely to the outer edge of the cylinder. 60 Surrounding this end of the cylinder are rings 23 and 24 spaced apart a distance equal to the width of the perforation in the cylinder 10. These rings support a cylinder or sleeve 25 which form together with the cylinder 10 and sleeve 25 an annular passage way or chamber 26. A drain pipe 27 is connected to the sleeve 25 and communicates with the chamber 26 and leads to the receiving tank not shown. Rods 28 are connected to the outer ring 23. Slidably mounted on these rods is the cylinder head 29 which is provided with openings 30 through which the rods project. The cylinder head is reduced in thickness or recessed on the inner face, leaving an annular rim 31. Secured to the rim is a perforated plate or screen 32 which with the reduced portion of the head forms a recess or chamber 33. 34 is a pipe which is connected to the head 29 and communicates with said chamber. To the outer end of this pipe may be secured a flexible pipe which leads to a receiving tank not shown. 35 is a cross bar which is carried by the rods or bolts 28. Threaded 75 through this cross bar is a bolt 36, the inner end of which takes against a block 37 which block bears against the head 29 and securely holds the head in place against the end of the cylinder. A short section of pipe 40 is 80 threaded at one end to the flange 16 of the T shaped sleeve 15. To the outer end of this pipe is secured the lower end of a funnel shaped connection 41. Secured to the other end of this connection is the tank C provided 85 with a removable cover c. A ram or plunger 45 fits snugly within the cylinder 10 and may be operated therein by any suitable means. As illustrated in the drawing, the means for operating the plunger consists of a lever 46, one end of which is pivoted at 47 to a bracket 48 secured to the base B. This bracket is provided with a series of openings 49, so that the point of pivot of the lever may be adjusted or varied. This lever is pivotally 90 connected to the plunger by a bolt 50, the lever being provided at this connection by a slot 51 to permit the lever to be moved in a manner well known. The free end of the lever may be supported by a bracket or 95 guide rest 52 secured to the base B. This lever may be operated by hand, pneumatic, 100

hydraulic or any other power, or the piston may be connected directly with the hydraulic operating or any other suitable means not shown.

5 The operation of the device is as follows:—

Assuming that the piston is withdrawn to the position in Fig. 3, and the cover *c* is removed from the tank *C*. The material to be 10 treated, garbage for instance, is thrown into the tank *C* when it will pass down through the funnel shaped connection 41 through the short pipe 40 through the openings in the sleeve 15 and cylinder 10 and into the said 15 cylinder. Power is then applied to force the piston inwardly and the material ahead of the piston is forced toward the perforated end of the cylinder. This movement compresses the material and forces the liquid carried by the 20 material through the screens and the perforations in the cylinder into the recesses or passage ways 26 and 33 where it flows out through the pipes 27 and 34 into the receiving tank not shown. The piston is now 25 withdrawn, which operation permits more of the garbage to fall into the piston when the piston is forced inwardly again and the second part of material ahead of the piston is compressed.

30 This operation is repeated until the perforated end of the cylinder 10 is full of the material to be compressed, which material is pressed until the solid matter is substantially freed of the liquid. When this is done, the 35 cylinder head is released by turning the bolt 36 in the proper direction and removing the block 37 whereupon the head 29 is slid on the bolts 28 to the position shown in Fig. 6. The plunger now is forced completely in- 40 ward when it will drive or force the compressed material out of the end of the cylinder. The cylinder head 29 is replaced and the pressing operation is repeated.

While I have shown certain features of my 45 invention in the accompanying drawings, it is to be understood that said drawings are merely illustrative, and that I am not con-

fined to what is there shown and herein de- 50 scribed, in connection therewith, except as may be specifically set forth in the claims.

Having now described my invention, what I claim as new and desire to secure by Letters Patent, is:—

1. In a device of the class described, a cylinder provided with separate chambers 55 having drain plugs therein, and perforated partitions for each of said chambers and forming walls for the cylinder, substantially as described.

2. In a device of the class described, a 60 cylinder, a magazine secured thereto and communicating therewith, a piston mounted in the cylinder through one end thereof, chambers at the other end of the cylinder, communicating therewith by a series of per- 65 forations, a removable head, and adjustable means for holding the head to the cylinder and means for reciprocating the piston or plunger.

3. In an apparatus of the class described, 70 a press cylinder having drainage means, a reciprocating imperforate ram, a head gate for said cylinder, said gate having drainage means, and means for reciprocating said ram in said cylinder.

4. In an apparatus of the class described, a cylinder having drainage means, a head gate removably secured to said cylinder, means for holding the head gate in line with the cylinder both in its operative and inop- 80 erative positions, said head gate having a cavity therein, a screen supported by said head gate and extending over said cavity and a ram adapted to reciprocate in said cylinder.

In witness whereof I have hereunto set my hand at the borough of Manhattan, city and State of New York, this fifth day of February, 1915.

ALBERT J. MORLOCK.

In presence of—

IRVING BLOUNT,
JOHN J. RANAGAN.
